(57) **CLAIM**

The ornamental design for a bicycle frame, as shown and described.

DESCRIPTION

FIG. 1 is a perspective view of a bicycle frame embodying the present invention.

FIG. 2 is a right side view of the bicycle frame of FIG. 1.

FIG. 3 is a left side view of the bicycle frame of FIG. 1.

FIG. 4 is a front view of the bicycle frame of FIG. 1.

FIG. 5 is a rear view of the bicycle frame of FIG. 1.

FIG. 6 is a top view of the bicycle frame of FIG. 1; and,
FIG. 7 is a bottom view of the bicycle frame of FIG. 1.

The broken lines in the drawings illustrate portions of the bicycle frame that forms no part of the claimed design.

1 Claim, 5 Drawing Sheets
